ILLUMINATED GLOBE MOUNTING

Raymond R. Dupler, Toledo, Ohio

Application May 22, 1936, Serial No. 81,250

3 Claims. (Cl. 240—2)

This invention relates to mountings for illuminated globes, such as terrestrial, astronomical or celestial globes and for which a globe or sphere is made of translucent material, such as glass, paper or a composition and in which is disposed an electric light bulb, thereby to illuminate the globe to facilitate study or inspection thereof.

An object of this invention is to produce a new and improved mounting for an illuminated globe to enable the globe to be readily and conveniently mounted or removed in a frame, particularly a frame in the form of a semicircle or complete ring.

Another object is to produce an illuminated globe structure having the novel features of construction, arrangement, and design hereinafter more fully described.

By way of illustration embodiments of the invention are shown on the accompanying drawing, in which—

Figure 1 is a side elevation of an illuminated globe and the mounting thereof, some parts being broken away and showing in dotted lines the manner in which the globe is assembled and removed relative to its supporting frame;

Figure 2 is an enlarged vertical section elevation on the line 2—2 of Figure 1 showing the mounting for the upper end of the globe; and

Figure 3 is an enlarged sectional elevation showing the pivotal mounting for the lower end of the globe.

The illustrated embodiment of the invention comprises an illuminated globe having a hollow base 10 on which is mounted a semicircular frame member 11, the diameter of the ring being disposed at an angle to and intersecting the vertical axis of the base 10. Manifestly the ring 11 corresponds to one-half of the meridian after the manner frequently followed in the mounting of terrestrial globes. Instead of a semi-circular ring being employed, a frame in the form of a circle may be employed.

Disposed within the frame 11 is a hollow globe or sphere 12 of glass, paper or a suitable composition sufficiently translucent to permit light from an electric light bulb to illuminate the exterior surface, it being understood that a terrestrial or celestial map may be provided on the globe 12, as by adhesively connecting the same thereto. The globe 12 is provided at one end, for example in the region of the south pole, with an aperture 13 in which is disposed an elongate tubular member 14 shouldered inside of the opening 13 at 15 and provided with a flange 16 disposed on the outside of and adhesively connected to the globe.

For supporting the lower end of the globe 12 a disc 17 having a peripheral flange 18^a is adapted to fit the shoulder 15 of the tubular member 14, the disc being annular so that the tubular member can turn and be guided upon the disc 17 thereby to enable the globe 12 to turn upon its axis. The disc 17 is in screw-threaded engagement with a post 18, the lower end 19 is reduced and extends into a grooved pocket 20 formed in the lower end portion of the frame member 11. A pin 21 passes transversely through the frame member 11 and the lower end portion 19 of the post and enables rocking or pivotal movement of the post relative to the frame.

Leading from the recess 20 is a groove 22 which merges in a vertical groove 23 leading to the hollow base 10. Through the grooves 23 and 22 extends an electric light cord 24. The light cord 24 extends through an opening 25 in the post 18 and thence upwardly through the post to a lamp bracket 26 on which is mounted an elongate electric light bulb 27 for illuminating the globe. The lamp bracket 26 is suitably fastened upon the outer end portion of the post 18 and since it may be of any suitable or well-known construction, further description thereof is not given. The lamp bracket 26 may contain a suitable switch actuated by a chain 21 which leads through an aperture 28 in the disc 17 and extends below the frame 11 to a position convenient for use.

Diametrically opposed to the aperture 13 is a relatively small aperture 29 in the globe 12. Extending through the aperture 29 is a tubular member 30 provided with a screw threaded portion 31 in the region of the aperture. Integral with the member 30 and disposed on the outside of the globe 12 is a flanged collar 32, a felt washer 33 being disposed between the collar and the globe. A nut 34 engages the screw threaded portion 31 and a felt washer 35 is interposed between the nut 34 and the inside of the globe. It is apparent by tightening the nut 34 the tubular member 30 will be held in position. Slidable in the tubular member 30 is a pin 36 having reduced lower end portion 37 and encircling the latter portion is a coil spring 38. A cotter pin 39 on the extension 37 is disposed on the outside of the tubular member 30 and holds the pin in place.

Extending transversely through the upper end of the frame member 11 is a relatively small opening 40 which terminates in a slightly larger portion or socket 41 at the lower end, the latter being of sufficient size to receive the pin 36. It will be observed that a bearing portion 42 is integral with the collar 32 and abuts against the adjacent 55

surface of the frame member 11. It will be apparent that the pin 38 cooperates with the frame 11 to provide a pivotal support for the upper end of the globe 12, enabling the latter to turn about its axis.

Assuming the parts are in the position shown by the full lines in Figure 1, the globe 12 may be removed by inserting a suitable tool, such as a nail, through the opening 48 in the frame member 11 to depress the pin 38 against the spring 39 sufficiently so that the pin is clear of the socket 41. The globe may then be tilted or rocked away from the frame member 11, the post 18 being mounted to swing about the pivot pin 21, enabling the globe to be tilted substantially to the dotted position shown in Figure 1. For this purpose it will be noted that the frame member 11 is provided with a lip portion 11a against which the adjacent side of the post may abut. When in this position the globe 12 may be lifted so that the tubular member 14 will clear and be free of the lamp bulb 27.

From the above description it is apparent that the globe may be readily and conveniently mounted on its frame without the use of any special tools and may be removed therefrom in an exceptionally simple manner. The parts are simply designed to enable them to be manufactured at a relatively low cost and the structure is sturdy and reliable. The globe is so supported that it can be turned freely to display different portions thereof.

Changes in details of construction, arrangement and operation may be effected without departing from the spirit of the invention, especially as defined in the appended claims.

What I claim is:

1. A globe mounting comprising a standard, diametrically opposed supports on said standard,

a globe carried by said supports, one support having a disengageable part adapted when released to free the globe therefrom, the other support having a member engageable with the globe and disposed substantially in axial alignment with said first support, a lamp associated with said other support and extending inside the globe, and means on said member providing a shiftable connection with the adjacent portion of the standard for enabling the member and globe to be moved laterally away from the standard upon release of said disengageable part.

2. A globe mounting comprising a base, an arcuate frame on said base, diametrically opposed supports on said frame, a globe carried by said supports, a disengageable part on one support for freeing the globe therefrom, a bearing member on the opposite support disposed substantially in axial alignment with said first support, a lamp associated with said other support and extending inside the globe, and means for pivotally mounting said bearing member on said frame for enabling rocking movement thereof relative to the adjacent portion of said frame to enable removal of the globe upon release of said disengageable member.

3. A globe mounting comprising a base, an arcuate frame on the base, diametrically opposed supports on said frame, a globe carried by said supports, one support comprising a releasable member, the other support comprising a post movably connected at one end to said frame, a bearing member on said post engageable with the globe, and a lamp support on the opposite end of said post having a portion extending inside of the globe.

RAYMOND R. DUPLER.
